UNITED STATES PATENT OFFICE.

LOUIS B. HARVEY, OF SAN FRANCISCO, CALIFORNIA, ASSIGNEE TO INTERLOCKING RIM
AND WHEEL COMPANY, OF SAN FRANCISCO, CALIFORNIA, A CORPORATION.

DISK-WHEEL.

1,307,005.

Specification of Letters Patent. Patented June 17, 1919.

Application filed May 21, 1918. Serial No. 235,887.

To all whom it may concern:

Be it known that I, LOUIS B. HARVEY, a citizen of the United States of America, residing at the city and county of San Francisco, State of California, have invented certain new and useful Improvements in Disk-Wheels; and I do declare the following to be a clear, full, and exact description of the same, reference being had to the accompanying drawings, and to the characters of reference marked thereon, which form a part of this application.

This invention relates to improvements in wheels, particularly to that type used on motor vehicles. The object of the invention is to produce a wheel in which metal disks may be substituted for the wooden or wire spokes now commonly used. The present invention is designed as an improvement over that structure shown in my pending application for patent, filed March 4th, 1918, Serial Number 220,161. In this present application, I also provide a reinforced disk mounted between the two outer disks in angular relation thereto so as to overcome the lateral side strain to which the wheel is subjected.

Also, the present invention provides an improved hub and rim connecting means.

A still further object of the invention is to produce a simple and inexpensive device and yet one which will be exceedingly effective for the purposes for which it is designed.

These objects I accomplish by means of such structure and relative arrangement of the parts as will fully appear by a perusal of the following specification and claim.

The figure of the drawings is a vertical section through the hub and one-half of the wheel, showing the construction thereof.

Referring now more particularly to the characters of reference on the drawings, the numeral 1 designates the axle of the wheel on the front end of which is keyed the hub cap 2.

The numeral 3 designates the mounting ring which is common to most wheels which are mounted on "full floating" axles, and is provided with the usual annular flange 4. In constructing my improved invention, I first provide a hub 5 having an inner bearing shoulder 6 which fits over the mounting ring 3. The hub 5 has an inner flange 7 extending at right angles thereto and an outer flange 8 which extends at an acute angle to the said hub 5.

The numeral 9 designates the outer rim or felly of the wheel which is made of metal and provided with a pair of downwardly projecting annular flanges 10 and 11. The inner edge of the felly 9 is provided with a V-shaped holding flange 12 arranged to receive an annular flange 13 on the demountable rim 14. An inner disk 15 is arranged to extend from between the flanges 4 and 7 to the flange 10. It is connected with the flanges 4 and 7 by bolts 16 and with the flange 10 by bolts 17.

The flange 8 projects to a point beyond the plane in which the outer edge of the rim 9 and the flange 11 lie, and an outer disk 18 is connected between the hub cap 2 and the flange 8 by means of bolts 19. This disk inclines upwardly toward the flange 11 until it reaches approximately the inner edge of such flange 11 when it bends back 75 and extends parallel to said flange 11, as at 18^a.

A reinforcing disk 20 is secured between the flanges 4 and 7 in parallel relation therewith and the same then bends and extends 80 obliquely to a point adjacent the inner edge of the flange 11 where it makes a return bend and extends parallel with the said flange 11, as at 20^a. A demountable ring 21 is arranged to be held against the edges 18^a and 20^a of 85 the disks 18 and 20 by means of nuts 17^a on the bolts 17, which bolts extend through the disk 15, flange 10, flange 11, edges 18^a and 20^a and ring 21. Thus, when the nuts 17^a are mounted on the bolt 17, the vertical 90 disks will be fixed rigid with respect to the felly 9. On the ring 21 is a V-shaped clamping flange 21^a adapted to engage the flange 13^a on the demountable rim 14 which carries the tire 22. When the ring 21 is bolted in 95 position, this flange 21^a securely clamps the demountable rim in position on the felly of the wheel.

My invention is the only one of the disk wheel type that I am aware of which provides for a demountable rim. Also, by means of the vertical securing bolts, the entire wheel may be readily disassembled for any purpose.

The obliquely extending disk 20, while 105 it fits at its edges parallel with respect to the vertical plane of the edges of the felly, at the same time it provides a lateral brace for the wheel to prevent it collapsing, due to any lateral strain brought to bear thereon. 110

From the foregoing description it will readily be seen that I have produced such a device as substantially fulfills the objects of the invention as set forth herein.

5 While this specification sets forth in detail the present and preferred construction of the device, still in practice, such deviations from such detail may be resorted to as do not form a departure from the spirit of
10 the invention, as defined by the appended claim.

Having thus described my invention, what I claim as new and useful and desire to secure by Letters Patent is:—

15 A disk wheel including a hub, a felly, a pair of inwardly projecting annular flanges

on the felly, a disk fixed to each end of the hub and extending adjacent each flange in parallel relation thereto, a third disk fixed to one end of the hub and inclined toward
20 the flange which lies in the plane opposite the hub end to which such disk is secured, such disk then bending to extend parallel to such flange, and bolts projecting through all the disks and flanges and having nuts to
25 bind the same together.

In testimony whereof I affix my signature in presence of two witnesses.

LOUIS B. HARVEY.
